COMBINED RECEPTACLE AND COMB

Robert Lester Motley, Dayton, Ohio

Application January 30, 1940, Serial No. 316,411

1 Claim. (Cl. 132—19)

This invention relates to a combined receptacle and comb.

One of the objects of the invention is to provide a comb attachment including a receptacle of sufficient length to receive hair pins or the like and to be mounted on a comb to be carried in the hair of the user.

Another object of the invention is to provide a convenient means for storing hair pins or the like and thus eliminates the necessity of carrying the same in a pocketbook or bag.

A further object of the invention is to provide a device of this character which may be formed from a single blank of sheet material and formed into the desired shape at a nominal cost.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming a part of this specification:

Figure 1 is a side elevation of the invention associated with a comb.

Figure 2 is a top plan of the device shown in Figure 1.

Figure 3 is a cross sectional view of the device.

Figure 4 is a perspective view of a modified form of the device.

Figure 5 is a plan view of the blank from which the preferred form of the invention is constructed.

Referring now to the drawing in which like characters of reference designate similar parts in the various views, in Figure 5 there is shown a blank of sheet metal having a rectangular portion 10 and an integral elongated substantially triangular member 11 merging at its apex with the center of one longitudinal edge of the rectangular member. The rectangular portion 10 is rolled longitudinally upon itself to form a tubular article retaining receptacle 12 for hair pins, or the like. One end of the container may be

closed by a plug 13 of any desired material, such as solder for example, and the other end is closed by a screw cap 14.

The member 11 is disposed to extend below and beyond the ends of the container 12, and is provided with openings adapted to receive securing pins 15 which are passed into one side of a straight or arcuate comb 16.

A modified form of the invention, as shown in Figure 4, is adaptable to a specially shaped comb back.

The comb 17 of the modified form includes a humped portion 18 progressively decreasing in width in triangular formation from the comb back to its apex and extends upwardly from the back midway its ends.

An article retaining container 19 of semi-circular cross section is secured to one side of the humped portion by ears 20 extending outwardly therefrom through which securing pins 21 are passed into the humped portion to position the container at right angle to the longitudinal axis of the comb back. A closure cap 22 is frictionally fitted on the upper end of the container and has its top wall flush with the apex of the hump.

From the above description it is thought that the construction and operation of the invention will be fully understood without further explanation.

What is claimed is:

A comb attachment formed from a single blank of material including an elongated substantially triangular member to be fixed adjacent its ends to the back of a comb with its apex edge uppermost and to extend along the length of the back and above the same, a rectangular member having one longitudinal edge formed centrally of its ends for a portion of its length on the upper edge of the triangular member, said rectangular member being rolled longitudinally to provide a tubular receptacle for receiving articles, means fixed on one end of the receptacle for closing the same, and a removable cap closing the opposite end of the receptacle and threaded thereon.

ROBERT LESTER MOTLEY.
